UNITED STATES PATENT OFFICE.

Louis N. D. WILLIAMS, OF OGONTZ, PENNSYLVANIA.

STITCH-TRANSFERRING DEVICE FOR KNITTING-MACHINES.

1,285,526.

Specification of Letters Patent. Patented Nov. 19, 1918.

Application filed April 3, 1916. Serial No. 88,594.

To all whom it may concern:

Be it known that I, LOUIS N. D. WILLIAMS, a citizen of the United States, residing in Ogontz, Pennsylvania, have invented certain Improvements in Stitch-Transferring Devices for Knitting-Machines, of which the following is a specification.

My invention relates to knitting machines which are equipped with web holders for engaging the sinker wales of a knitted web to prevent rise of the stitches with the needles, and particularly to machines from which the web can be removed by engagement with a series of transfer points, one object 10 of my invention being to prevent withdrawal of the web from the transfer points during such removal, another object being to prevent reengagement of the needles with the stitches which have been cast therefrom, a further object being to provide for engagement 20 of the transfer points with a course of stitches preceding the terminal course without unduly weakening the top of the needle carrier, another object being to improve the construction of that portion of the machine 25 which acts as a guide for the web holders, and a still further object being to insure the knocking over of the terminal stitches.

These objects I attain in the manner hereinafter set forth, reference being had to the accompanying drawings, in which—

Figure 1 is a transverse sectional view of part of a knitting machine embodying certain features of my invention, the parts being shown in the positions assumed by them when the transfer points are applied to the terminal stitches upon the needles;

Fig. 2 is a similar view showing the transfer points engaged with the stitches and the latter cast from the needles;

Fig. 3 is a similar view showing the needles again raised but out of range of the cast stitches and the web holders retracted so as to release the web;

Fig. 4 is a view similar to Fig. 1 but showing the application of the transfer points to a course of stitches preceding the terminal course;

Fig. 5 is a horizontal section of part of the machine with a top view of the web holder actuating cams;

Fig. 6 is a side elevation of part of the machine;

Fig. 7 is a view similar to Fig. 4, but illustrating another feature of my invention, and

also another means for effecting the thrusting out of the needles;

Fig. 8 is a similar view illustrating still another means of thrusting out the needles;

Fig. 9 is a vertical sectional view of the upper portion of a needle carrier illustrating another means for effecting the outward thrust of the needles therein;

Fig. 10 is a similar view illustrating the application of this feature of my invention to a needle carrier having a drop head, and

Fig. 11 is a face view of a certain member of the device looking in the direction of the arrow Fig. 13.

My invention can be applied to knitting machines whether of the circular or flat bed type but for convenience the invention is shown in the drawings as applied to a circular machine, and to prevent confusion no attempt has been made to show the stitches in the distant portion of the knitted web, the same being represented as a close web which hides everything behind it.

In the drawings, 1 represents the needle carrier of the machine, 2 the needles, 3 the carrier for the cams whereby the reciprocation of the needles is effected, 4 the web holders, 5 the web holder carrier, and 6 the carrier for the cams whereby the radial reciprocation of the web holders is effected.

In the machine shown in Figs. 1 to 4 there is, behind each needle, a jack 7 with enlarged head 8 contained in a recess 9 in the needle carrier and said recess has at the top two steps 10 and 11, each with inclined lower end. The butts at the lower ends of the jacks 7 are acted upon by a swinging lifter cam 12 and by a swinging depresser cam 13, the lifter cam 12 being adjustable to the position shown by full lines in Fig. 6 or to either of the dotted line positions there shown, and the depressing cam 13 being also adjustable either to the full line position or to the dotted line position shown in said figure.

The transfer points 15 are suitably mounted in a carrier 16 and below the latter is a guide and stripper 17 which is notched or slotted for the reception of the points 15 and the upper ends of the corresponding projected needles 2, consequently when this stripper 17 is applied to the needles, prior to the depression of the point carrier 16, it will properly register each of the points 15 with its corresponding needle, and, when the

carrier 16 is depressed, as shown in Fig. 1, will direct each point behind its corresponding needle and into the corresponding stitch.

When applying the transfer points to the 5 terminal stitches of the web, that is to say, to the stitches still upon the needles, the cam 12 is, before depressing the point carrier, adjusted to the position shown by dotted lines ^a Fig. 6, thus raising the heads 8 of the jacks

10 7 onto the first step 10 and throwing the upper ends of the needles radially outward, as shown in Fig. 1, so that the points 15 can pass freely between the needles and the needle carrier.

15 In order to free the terminal stitches from the needles the latter are, after engagement of the transfer points with the stitches, retracted so as to cast off said stitches, as shown in Fig. 2, and before the needles are

20 again raised the cam 12 is swung to the position shown by dotted lines ^y in Fig. 6, so as to raise the heads 8 of the jacks 7 onto the second step 11, thereby throwing the upper ends of the needles radially outward to the

25 fullest extent, as shown in Fig. 3, whereby, when the needles again rise, they will not enter the stitches which they had before cast off.

At the same time the web holders 4 are re- 30 tracted and permitted to remain in their retracted position thus freeing the transferred stitches of the web from the restraining influence of the hooks 20 of the web holders in order that the latter may not interfere with

35 the free removal from the machine of the transfer points with the web upon them. After removal of the web the web holders are restored to operative position and the jacks 7 are lowered by swinging the cam 12

40 to the position shown by full lines in Fig. 6, and the cam 13 to the position shown by dotted lines in said figure, said cam 13 being again raised after all the jacks have been depressed.

45 In order to prevent any clamping of the stitches of the web or parts of the same between the inserted points and the projecting stems 21 of the web holders the retraction of the web holders is, by preference, to such

50 an extent as to withdraw said stems 21 beyond the range of the transfer points, as shown in Fig. 3, but in order that such release of the stitches may be effected without at the same time removing the stems of the

55 web holders from engagement with their guide slots the inner end of the stem of each web holder is recessed at the top so that while such recessed portion may be withdrawn beyond the range of the transfer

60 points, as shown in Fig. 3, the lower portion of the stem will still project into the guide slot, as shown at 23 in said figure.

In order to permit all of the web holders to be retracted to the position shown in Fig. 6 3 and retained in this retracted position as

long as necessary, the web holder projecting cams 24 and 25 of the cam ring 6 are adjustable to inoperative position, as shown by dotted lines in Fig. 5, and when in this position will permit the butts of the web holders, which have been retracted by the cam 22, to remain in this retracted position, as shown by dotted lines, until said projecting cams have again been restored to operative position.

In many cases, especially if the knitted web is of fine gage, it is advisable to engage the transfer points with stitches of a course of knitted web preceding the terminal course thereof, but owing to the tendency of the web to twist, the course with which the transfer points engage must be relatively close to the terminal course, otherwise such twisting tendency will draw the stitches of the course which is to be engaged out of registry with the transfer points which are intended to engage the same.

If, however, the top of the needle carrier has to be cut away for the reception of the transfer points, such a reduction in the thickness of the wall at the upper end of the carrier so results as to unduly weaken the same. In order to overcome this objection I provide the needle carrier with a separate head 26 movable in the direction 95 of the reciprocating movement of the needles, hence while during the knitting operation the upper edge of said head 26 may be substantially flush with the upper edges of the stems 21 of the web holders, as shown in Figs. 1, 2 and 3, such head may be retracted, as shown in Fig. 4, in order to permit engagement of the transfer points with the stitches of a course of knitted web preceding the terminal course but relatively close thereto, said head being restored to its normal position again after the removal of the transfer points with the web upon them and before resuming the knitting operation.

The web holder carrier 5 has formed therein, below the web holders, a lint collecting chamber 27, and in order to prevent any access of lint to the gap between the upper end of the cylinder and the lower portion of the head 26 when the latter is raised, the needle guide ribs 28 on the carrier 1 are extended above the top of the same across said gap, as shown in Figs. 1, 2 and 3, whereby said ribs and the intervening needles 2 serve to practically close the gap.

In carrying out my invention other means than the jacks 7, cam 12 and cam steps 10 and 11 may be employed as a means for causing the outthrust of the needles 2 in 125 their grooves. For instance, in Fig. 7 I have shown the vertically adjustable head 26 as provided with an internal cam 32 which, when said head is depressed, as shown in Fig. 7, acts upon a surrounding spring 33 130

so as to expand the same and cause it to impart outward thrust to each of the surrounding needles, and in Fig. 8 I have shown a cam ring 34 disposed within a fixed head 26^a on the cylinder so as to be capable of a limited amount of vertical movement therein, this cam ring acting upon the spring 33 so as to impart outward thrust thereto as the ring is raised, said raising movement being conveniently imparted to the cam ring by providing the same with projecting studs 35 adapted to inclined slots 36 in the head 26^a, whereby, when a partial turn is imparted to the cam ring 34, it can either be raised, so as to expand the spring 33, or can be lowered so as to relieve said spring from such expansion.

In the construction shown in Fig. 9 the cam, which acts upon the expansion spring 33 is formed in the outer face of the needle carrier, and said spring is acted upon by fingers 50 which project inwardly between the needles 2 and are carried by an angular bar 51 mounted on the web holder carrier 5 so as to be free to move vertically thereon, said bar 51 being depressed by engagement of a pin 52 on its outer face with a cam slot 53 in an angle plate 54 likewise mounted on the web holder carrier 5 so as to be free to have a certain amount of movement thereon in a horizontal plane.

When the machine is knitting normally the needles occupy a normal position in the bases of the needle guiding grooves of the needle carrier, the bar 51 occupies its elevated position and the expansion spring 33 is above the cam surface of the needle carrier, all as shown in Fig. 9. By a slight lateral movement of the plate 54, however, the cam slot 53 thereof is caused to act upon the pin 52 of the bar 51 so as to depress the same, thereby forcing the spring 33 down into engagement with the cam surface of the needle carrier and causing consequent expansion of said spring and out-thrust of the needles from the bases of the needle grooves in substantially the same manner as in the other embodiments of this feature of my invention which I have shown.

In Fig. 9 I have shown this feature of my invention as applied to a needle carrier having a fixed head, but in Fig. 10 I have shown the spring 33 as acted upon by a bar 55, which is slotted at the top for the guidance of the web holders, and is in vertical engagement with one or more of the fingers 50 of the bar 51 so as to be caused to move vertically with the latter, said bar 55 thus constituting the equivalent of the drop head 26 as shown in Figs. 3 and 4.

In the construction shown in Figs. 7, 8, 9, and 10 a single cam only is employed in place of the two-step cam shown in Figs. 1 to 4, only one degree of outward thrust being imparted to the needles.

In those figures of the drawings in which the stitches of the web are shown such stitches are for ease of illustration represented as of a much coarser gage than they would be in practice.

70

I claim:

1. The combination of the needles and web holders of a knitting machine, with a series of transfer points for engaging stitches of the knitted web, means for retracting the web holders so as to free them from engagement with the web, and means for permitting them to remain in such retracted position while the transfer points, with the web upon them, are being removed from the machine.

75

2. The combination of the needles of a knitting machine, a series of transfer points, a carrier therefor, and a guide constructed to receive said points and also to receive the corresponding needles of the machine in order to register the points with said corresponding needles.

80

3. The combination of the needles of a knitting machine, a series of transfer points for engaging stitches of the knitted web, reciprocating web holders having guide stems recessed at their inner ends, and means for retracting said web holders so that said recessed inner ends of the same will be withdrawn into the plane of the transfer points.

85

4. The combination of the needles and needle carrier of a knitting machine, with transfer points for engaging stitches of the knitted web, said needle carrier having a head movable in respect thereto, whereby it can be withdrawn out of the way of the transfer points when the latter engage the stitches of a course preceding the terminal course.

90

5. The combination of the needles and web holders of a knitting machine, transfer points for engaging stitches of the knitted web, and a needle carrier having a head serving as a guide for the stems of the web holders but susceptible of being withdrawn out of the way of the transfer points when the latter engage the stitches of a course preceding the terminal course of the knitted web.

95

6. The combination of the needle carrier and needles of a knitting machine, said needle carrier having a movable head and projecting ribs with intervening grooves for the reception and guidance of the needles, said ribs bridging the gap between the needle carrier and the movable head of the same when said head is projected.

100

7. The combination of a needle carrier and its needles, a cam, an elastic medium interposed between such cam and the needles, and means whereby the cam, through said elastic medium, is caused to act upon the needles to thrust them outwardly in their grooves.

105

8. The combination of the needle carrier

110

115

120

125

130

and its needles, a cam, an elastic medium interposed between said cam and the needles, and means for moving one of said elements in respect to the other so as to cause expansion of said elastic medium and outward projection of the needles, or so as to permit said elastic medium to contact and permit the needles to resume their former position.

In testimony whereof, I have signed my name to this specification, in the presence of 10 two subscribing witnesses.

LOUIS N. D. WILLIAMS.
